[57] CLAIM

The ornamental design for a aspiration-type sprayer, as shown and described.

DESCRIPTION

FIG. 1 is a right side elevational view of the aspiration-type sprayer;

FIG. 2 is a top plan view of the aspiration-type sprayer;

FIG. 3 is a left side elevational view of the aspiration-type sprayer;

FIG. 4 is a bottom plan view of the aspiration-type sprayer;

FIG. 5 is a front view of the aspiration-type sprayer; and,

FIG. 6 is a rear view of the aspiration-type sprayer. The broken line showing is for illustrative purposes only and forms no part of the claimed design.
